US00D621515S

(12) **United States Design Patent**
Chua et al.

(10) **Patent No.:** US D621,515 S
(45) **Date of Patent:** ** Aug. 10, 2010

(54) **SKIN ANALYZING DEVICE**

(75) Inventors: **Cony Nan-Sing Chua**, Edison, NJ (US);
Sandy Lam, Singapore (SG); **Kukizo Miyamoto**, Ashiya (JP); **Takashi Yoshii**, Yasu (JP)

(73) Assignee: **The Procter & Gamble Company**, Cincinnati, OH (US)

(**) Term: **14 Years**

(21) Appl. No.: **29/315,174**

(22) Filed: **Jun. 2, 2009**

(51) **LOC (9) Cl.** **23-01**

(52) **U.S. Cl.** **D24/186**

(58) **Field of Classification Search** D24/107,

(57) **CLAIM**

The ornamental design for skin analyzing device, as shown and described.

DESCRIPTION

FIG. 1 is a perspective view of skin analyzing device showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom view thereof.

The broken lines shown are included for the purpose of illustrating a portion of the skin analyzing device that forms no part of the claimed design.
